ALBERT ABBINK, OF FIRTH, NEBRASKA, ASSIGNOR OF ONE-FOURTH TO RICHARD ABBINK, ONE-EIGHTH TO JACOB C. RUIGH, AND ONE-EIGHTH TO JOHN DOESCHOT, ALL OF FIRTH, NEBRASKA

GATE FOR TRAP NESTS

Application filed April 25, 1931. Serial No. 532,953.

This invention relates to improvements in trap nests and pertains particularly to an improved gate structure.

The primary object of the present invention is to provide a novel swinging gate for a hen's nest, which will be automatically closed by the hen when entering the nest so that the entry of other hens will be prevented and the hen upon the nest cannot be disturbed. The hen upon leaving the nest also forces the gate to an opened position which it maintains until another hen's entrance.

Another object of the invention is to provide a novel type of nest gate which is of strong and durable construction but simple in design and therefore unlikely to get out of order.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

30 In the drawings:—

Figure 1 is a view in front elevation of a nest structure equipped with the gate embodying the present invention;

Figure 2 is a vertical sectional view 35 through the central part of the nest and transversely of the gate showing the latter opened;

Figure 3 is a vertical sectional view taken on the line 3—3 of Figure 1.

40 Referring more particularly to the drawings wherein like numerals of reference designate corresponding parts throughout the several views, the numeral 1 indicates generally a nest box in one wall of which an entrance opening 2 is formed. The top edge of the entrance opening has a recess 3 formed therein, above which, upon the outer face of the box wall, the present gate structure is attached.

50 The gate structure embodying the present

invention comprises a plate or door 4 which is secured at its top edge to one leaf of a hinge member 5, the other leaf being secured in vertical position to the face of the wall in which the opening 2 is formed, above the top edge 55 of the opening and across the recess 3.

The fixed leaf of the hinge 5, which is indicated by the numeral 6, has an opening 7 formed therethrough and above this opening there is secured to the front of the leaf, one leaf of a smaller hinge 8. The other leaf of the hinge 8 swings freely in the opening 7 and there is attached to the inner face thereof one end of an arm 9 which normally extends into the nest chamber. This arm constitutes a 60 trigger by which the door 4 is released to swing to closed position, as will be hereinafter described.

The leaf of the hinge 5 which is attached to the door 4, has secured thereto one end 70 of a finger member 10. This finger extends inwardly from the door and is then bent to project outwardly across the top edge thereof so that when the door 4 is swung outwardly its free end will move back into a position 75 where it will hook against the swinging leaf of the hinge 8, the trigger 9 passing over the top thereof. The trigger 9 acts as a balance to cause the free leaf of the hinge 8 to swing forwardly when the door 4 is oscillated outwardly so that there is co-ordinated movement between the finger and the trigger.

80 From the foregoing description it will be readily seen that when the trap nest door is in the opened position shown in Figure 2, the trigger 9 projects downwardly partly across the entrance opening so that a hen entering the nest will strike this trigger and lift it out of engagement with the end of the finger 5. This will permit the door to gravitate to 85 closed position.

When the hen wishes to leave the nest she will force the door 4 outwardly and thus swing the finger 10 inwardly to the position where the free end thereof will hook behind the swinging leaf of the hinge 8, in the manner previously described. The door or gate will thus be held in opened position until another hen enters the nest.

95 The lower edge of the door or gate 4 is pro- 100

vided with an opening 11 through which the hen may extend her head when attempting to leave the nest and thus enable her to lift the door on her back rather than by her head.

Having thus described the invention, what is claimed is:

1. In a nest structure of the character described having an entrance opening through one wall, a gate for said entrance opening, hinge means between the top edge of said gate and the top of said opening, an elongated trigger arm having pivotal connection at one end with the top edge of said opening and normally extending into the nest, a shoulder forming a part of said trigger structure, and a curved finger member having one end secured to the inner face of the gate adjacent the top edge and having the other end directed across the top edge of the gate and disposed in the same vertical plane as the trigger to engage said shoulder by its free end when the gate is swung to opened position.
2. In a nest structure of the character described having an entrance opening through one wall, a gate for said entrance opening, hinge means between the top edge of said gate and the top of said opening, an elongated trigger arm having pivotal connection at one end with the top edge of said opening and normally extending into the nest, a shoulder forming a part of said trigger structure, and a curved finger member having one end secured to the inner face of the gate adjacent the top edge and having the other end directed across the top edge of the gate and disposed in the same vertical plane as the trigger to engage said shoulder by its free end when the gate is swung to opened position, said finger being formed and arranged to support the trigger member in horizontal position in the nest, when the gate is in closed position.
3. In a nest of the character described having a wall with an entrance opening therethrough, a gate for said opening, a hinge member having one leaf secured to said gate at the top edge thereof and having its other leaf secured to the face of the wall through which the entrance opening is formed and at the top of the opening, said wall attached leaf having an opening formed therethrough, a second hinge having one leaf secured to the wall attached leaf and having its other leaf swinging freely in the leaf opening, a trigger arm secured at one end to said freely swinging leaf and normally extending into the nest, and a finger member secured at one end to the upper part of the gate and curved intermediate its end to have its other end directed across the top of the gate, the said other end of the finger being designed for engagement against an edge of the freely swinging hinge leaf to maintain the gate open and said trigger in a position to be engaged by a hen entering the nest.

4. In a nest of the class described, having an entrance opening, a hanging gate hingedly mounted to cover the opening and means coacting with the gate to maintain the same open and at the same time arranged for contact with a bird entering the nest to close the gate, and to latch and retain the gate in open position when pushed to such position by the bird leaving the nest.

5. In a nest of the class described having an entrance opening, a gate suspended to close said opening and having a hinge mounted adjacent the top of the opening, a trigger element hinged adjacent the top of said opening, said gate swinging inwardly upon closing and said trigger element swinging downwardly toward the opening upon the opening of the gate, and means coupling the upper portion of the gate with the trigger element when the gate is open whereby the trigger element is held in operative position by the weight of the gate.

6. In a nest of the class described having an entrance opening, a hanging gate hingedly mounted to swing to a position to close said opening, an elongated trigger element pivotally mounted adjacent the top of the gate, a hook element carried by the gate, and means for coupling the hook element with the trigger element to maintain the gate in outwardly directed open position and to maintain the trigger element in inwardly and downwardly directed set position for engagement by a bird passing through the opening.

7. In a nest of the class described having an entrance opening, a hanging gate hingedly mounted to gravitate to a position to close said opening, an elongated trigger element hingedly mounted adjacent the top of the opening, and means for engaging the gate with the trigger element to maintain the latter in inwardly and downwardly directed set position and to maintain said gate open, said means being designed to automatically operate to maintain the trigger and gate in such positions, when the gate is pushed outwardly from closed position by a bird leaving the nest.

In testimony whereof I hereunto affix my signature.

ALBERT ABBINK.
